UNITED STATES PATENT OFFICE.

GEORGE SHINE, OF BANGOR, MICHIGAN.

GATE.

SPECIFICATION forming part of Letters Patent No. 663,366, dated December 4, 1900.

Application filed July 31, 1900. Serial No. 25,465. (No model.)

To all whom it may concern:

Be it known that I, GEORGE SHINE, a citizen of the United States, residing at Bangor, in the county of Van Buren and State of Michigan, have invented a new and useful Gate, of which the following is a specification.

The invention relates to improvements in gates.

One object of the present invention is to improve the construction of gates and to provide a double one adapted when opened to afford an opening or gateway of great width to permit vehicles with bulky loads and agricultural machinery and the like to pass through them readily.

A further object of the invention is to provide a double gate of this character which may be adjusted vertically to counteract sagging and to provide an entrance or opening at the bottom for the separation of small animals and also to permit the gate to clear obstructions, such as snow and the like.

Another object of the invention is to provide an adjustable keeper which may be readily arranged to suit the position of the adjustable gate, so that the latter will close properly at all times.

The invention consists in the construction and novel combination and arrangement of parts hereinafter fully described, illustrated in the accompanying drawings, and pointed out in the claims hereto appended.

In the drawings, Figure 1 is an elevation of a double gate constructed in accordance with this invention. Fig. 2 is a plan view of the same. Fig. 3 is a detail perspective view of the adjustable keeper. Fig. 4 is a similar view of the keeper, which is engaged by the resilient latch. Fig. 5 is a detail view of the resilient latch of the supplemental gate. Fig. 6 is a detail view of one of the staples which form the guide for the vertically-adjustable bar of the main gate. Fig. 7 is a detail perspective view illustrating a modification of the latch and keeper for securing the supplemental gate.

Like numerals of reference designate corresponding parts in all the figures of the drawings.

1 and 2 designate supplemental and main gates having their free edges arranged at their adjacent ends and hinged at their outer ends,

and the main gate, which is of greater length than the supplemental gate, is connected by upper and lower hinges 3 and 4 with a vertically-adjustable bar 5. The main and supplemental gates may be constructed in any desired manner, and the vertically-adjustable bar 5, which carries the main gate, is arranged in a guide consisting of vertically - aligned staples 5, projecting from a post 6, and each staple is provided with a threaded extended side 7, adapted to be screwed into the post 6 by rotating the staple. The other side of the staple is provided with an eye 8, arranged flat against the post 6 when the staple is in position and adapted to receive a screw or other suitable fastening device for holding this side of the staple. The bar 5 is adapted to be raised and lowered to arrange the gate at the desired elevation, and the weight of the gate will cause the bar 5 to bind against the post and the upper staple, whereby the main gate will be securely held in its vertical adjustment.

The main gate is provided with a spring-actuated latch 10, and it has a pointed rod 11, mounted in suitable guides and adapted to have its lower pointed end embedded in the ground for holding the gate open. The spring-actuated latch, which may be constructed in any suitable manner, projects beyond the free end of the main gate and is adapted to engage a vertically-adjustable keeper 12, consisting of a pair of vertical bars 85 connected by adjusting devices and engaging tongues or projections 13 of the supplemental gate. The adjusting devices 14, which connect the bars of the main keeper, consist, preferably, of bolts and thumb-nuts and are arranged at the upper and lower portions of the bars, which are provided with flat inner faces and which are spaced apart by the tongues of the supplemental gate. The bars of the main keeper are provided with beveled intermediate portions 15, adapted to be engaged by the spring-actuated latch when the main gate closes, whereby the latch is automatically forced inward or backward and is caused to project into the space between the bars 12, whereby the main gate is held in its closed position. The adjusting devices which cause the bars of the main keeper to clamp the tongues or projections 13 of the supple-

mental gate enable the keeper 12 to be readily set at the desired elevation to correspond to the position of the main gate.

The hinges 3 and 4 of the main gate may 5 be of any desired construction, but are preferably of the form shown, being composed of pintles and eyes mounted, respectively, on the bar 5 and on the end bar of the main gate. The hinges 16 of the supplemental gate may 10 be of any desired construction, but are preferably strap-hinges and are arranged at one side of the supplemental gate, as clearly illustrated in Fig. 2 of the accompanying drawings.

15 The supplemental gate, which is adapted to be opened when a gateway of great width is desired, is provided at one side with a horizontally-disposed resilient latch 17, consisting of a shank 18 and an arm or projecting portion. The shank is secured to the gate, as clearly shown in Fig. 1, and the arm or projecting portion, which is resilient, is arranged at an angle to the supplemental gate and extends toward the hinged end thereof 20 at an acute angle to that end of the gate, and it is provided at its extremity with an angularly-disposed projection or lug 19. The projection or lug which extends inward toward the fence 20, when the supplemental gate is 25 closed, is adapted to engage a supplemental keeper 21, consisting of a strip of metal which is bent to form an arm 22 and a brace 23, the brace being provided with an extension or shank 24, which is secured to the fence. 30 The arm and the brace form a substantially elbow-shaped keeper, and an opening 25 is provided at the angle for the reception of the lug or projection. The angle of the elbow is slightly rounded, as shown, and it forms an 35 exterior beveled or angularly-disposed portion, which is adapted to flex the resilient latch and cause the lug or projection to spring into the opening or aperture 25, whereby both the gates will be held firmly in their closed 40 position. When it is desired to open the supplemental gate, the resilient latch is sprung out of engagement with the substantially V-shaped keeper, which operation leaves the gate free to open, and it is adapted to swing 45 around against the fence. When the supplemental gate is closed, the resilient latch 17 is automatically engaged with the supplemental keeper.

In Fig. 7 of the drawings is illustrated a 50 modification of the latch and keeper of the supplemental gate. This latch consists of a hook 26, and the keeper 27, which is approximately V-shaped, is constructed of wire or other suitable material coiled at the apex to 55 provide an eye or opening 28 to be engaged by the hook. The hook is preferably hinged to the gate, as illustrated in Fig. 7, and the keeper has one side embedded in the post or other portion of the fence, and the other side 60 is perforated for the reception of suitable fastening devices for securing it to the fence.

This form of latch and keeper is efficient and may be cheaply manufactured.

It will be seen that the double gate is exceedingly simple and inexpensive in construction, that the main gate is adapted to be opened and closed independently of the supplemental gate, and that it is capable of being readily adjusted vertically to counteract sagging, to enable it to clear obstructions, 75 and to provide a passage-way for small animals to facilitate the separation of stock. Furthermore, it will be seen that the keeper 12 is vertically adjustable, is adapted to be arranged at an elevation to correspond to the 80 position of the main gate, and that it is readily detachable.

Changes in the form, proportion, size, and the minor details of construction may be resorted to without departing from the spirit 85 or sacrificing any of the advantages of the invention, such as varying the construction of the main and supplemental gates and the fence to which the supplemental elbow or V-shaped keeper is applied. 90

What I claim is—

1. The combination with a vertically-adjustable main gate, and a supplemental gate, of a resilient latch located adjacent to one end of the supplemental gate and extending 95 from one side thereof, a rigid keeper mounted on a suitable support and arranged to be engaged by the resilient latch, a vertically-adjustable main keeper mounted on the supplemental gate and composed of two bars spaced 100 apart, and a latch mounted on the main gate and engaging the vertically-adjustable keeper, substantially as described.

2. The combination with a vertically-adjustable main gate provided with a latch, a support, a supplemental gate hinged to the support, a keeper mounted on the supplemental gate at the free edge thereof and engaged by the latch of the main gate, an approximately V-shaped keeper extending outward from the support and provided at its apex with an opening, and a latch carried by the supplemental gate and engaging the opening of the V-shaped keeper, substantially as 115 described.

3. The combination with a vertically-adjustable main gate, and a supplemental gate, of a vertically-adjustable keeper mounted on the free edge of the supplemental gate and composed of two bars provided with beveled 120 portions and spaced apart, and adjusting devices arranged transversely of the bars and connecting the same and clamping them on the supplemental gate, a stationary keeper, and a latch mounted on the supplemental 125 gate and engaging the stationary keeper, substantially as described.

4. The combination with a vertically-adjustable main gate, and a supplemental gate, a keeper mounted on the supplemental gate 130 at the free edge thereof, and a latch carried by the main gate for engaging the said

keeper, of a resilient laterally-extending latch mounted on the supplemental gate, and a stationary keeper arranged to be engaged by the resilient latch, substantially as described.

5. The combination with a support, a main gate, and a supplemental gate hinged to the said support, a keeper fixed to the support, a latch mounted on the supplemental gate and engaging the said keeper, a latch carried by the main gate, and a keeper mounted on

the supplemental gate at the free edge thereof and arranged to receive the latch of the main gate, substantially as described.

In testimony that I claim the foregoing as my own I have hereto affixed my signature in the presence of two witnesses.

GEORGE SHINE.
